UNITED STATES PATENT OFFICE.

GARY S. POWELL, OF KANSAS CITY, MISSOURI, ASSIGNOR TO THE LAMSON COMPANY, OF BOSTON, MASSACHUSETTS, A CORPORATION OF NEW JERSEY.

WIRE-LINE BASKET-CARRIER APPARATUS.

1,176,852.

Specification of Letters Patent. Patented Mar. 28, 1916.

Application filed January 26, 1914. Serial No. 814,279.

To all whom it may concern:

Be it known that I, GARY S. POWELL, a citizen of the United States, residing at Kansas City, in the county of Jackson and State of Missouri, have invented certain new and useful Improvements in Wire-Line Basket-Carrier Apparatus, of which the following is a specification.

This invention relates to carrier despatch apparatus and more particularly to wire-line basket carrier systems of this description and has for one of its objects the provision of means for automatically locking the carrier, at either end of the line, against inadvertent despatch or movement when the basket or receptacle has been lowered or detached therefrom.

A further object is to preferably mount all movable locking or lock actuating elements upon the carrier itself so that said elements travel therewith. This tends toward simplification of the apparatus in so far at least as the accomplishment of the first mentioned object is concerned.

These and other objects of my invention will be hereinafter referred to and the novel means and combinations of elements whereby said objects are attained will be more particularly set forth in the claims appended hereto. I am aware, however, that various changes and modifications may be made in the construction given by way of exemplification and I hence desire to be limited only by the scope of said claims.

In the accompanying drawing which forms a part hereof and in which like reference characters designate like parts in the respective views, I have shown a preferred embodiment of my invention.

Referring to the drawing: Figure 1 is a partial side elevation of a wire-line basket carrier apparatus; portions thereof being broken away for convenience of illustration. Fig. 2 is a side elevation of the carrier

proper, also partly broken away. Fig. 3 is a plan view of said carrier; and Fig. 4 is a detail view of the basket or receptacle locking mechanism; together with fragments of the latch bolts, etc.

The track 1 and guide wire 2 may be of the usual construction; and the commonly provided hanger 3, its station bracket 4 and

associated parts may be such as are in common use, no claim being made to these parts of the apparatus. A wheeled carrier 5 rides upon track 1 and is adapted to support a receptacle or basket 6; a suitable locking mechanism adapted to be operatively engaged with and disengaged from the supporting frame 7 of the basket by alternate pulls upon the hoisting cord 8, being provided in connection with said carrier.

A lock similar to that shown in detail in Fig. 4 has been disclosed in the patent to Gipe No. 645,505, dated March 13, 1900; so that the construction of the present lock need be but cursory. It comprises a knuckle 9 pivoted to the carrier frame at 10 and normally pressed into the position in which it is shown by a spring 11 the outer end of which bears against a pin 12 which projects inwardly from the side of the carrier frame which has been broken away. This knuckle is adapted to receive a portion of the basket frame, at 13 and to be rotated thereby, as in said Gipe construction.

Pivoted to the carrier frame at 14 is a spring actuated dog 15, the spring whereof is shown at 16 in Fig. 3. This dog is provided with a tooth 17 which engages the flank 18 of the knuckle when the latter has been rotated counter-clockwise (as viewed in Fig. 4) by its engagement with the usual bar of the basket frame; the dog 15 being then free to drop into its dotted-line position. When the locking device is in its open position however, in the present construction, tooth 17 bears downwardly against the arcuate surface 19 of the knuckle which holds the dog in its full line position as shown.

The dog 15 carries a trigger 20, pivotally connected thereto; a flat spring 21 normally holding the trigger in definite relationship with respect to the dog. As in the Gipe construction, this trigger is raised from its dotted-line position, which it occupies when the locking device is operatively disposed, to its full-line position by the stirrup 22, whereby to elevate the dog and thereby release the knuckle to permit of the withdrawal of the basket frame from its engagement with the carrier; the stirrup being raised and lowered in the usual manner by the

cord 8. The dog 15 has, in my preferred construction, an extension 15', the function of which will be hereinafter referred to.

Pivoted to each end of the carrier are 5 spring pressed latch elements 23 which are adapted to be snapped into engagement with hooks or relatively fixed latches 24, one of which is disposed at the station at each end of the line. These latch parts 24 are preferably mounted upon rods 25 which are centered or positioned with respect to the respective brackets 4 by buffer and recoil springs 26 and 26'. Extensions 24' of parts 10 24 also have threaded through them the lower or guide wire 2, to hold said parts against rotation. These extensions also each frictionally engage a lever 27, which is pivoted at 28 to the corresponding bracket 4, and which, further, has attached thereto an 15 upstanding link 28' to which is suitably connected (as by means of a clevis which is also pivotally connected to an arm 29' of the station) the corresponding end of the track-wire 1. Obviously as the carrier approaches 20 one or the other of the stations its weight tends to rock down the arm 29' and thereby the lever 27 of the station being approached, with consequent increase of pressure upon the extension 24' in engagement with said lever. Then as the carrier latch element 25 23 upon the forward end of the carrier trips over the hook 24 and drives the latter rearwardly against spring 26, the extension 24' of the hook wipes against the friction surface 30 of lever 27 and aids in gradually arresting the carrier and also in preventing a too violent recoil of spring 26.

Referring now more especially to Figs. 2 and 4, it will be noted that two bolts 29 and 30 are slidably mounted in the respective ends of the carrier, said bolts extending through suitable apertures in the ribs 31 and 32 of the carrier frame. Each bolt has the outer extremity thereof preferably 45 flattened upon one side to better adapt it for locking engagement with the corresponding pin or cross-bar 33 within each of the U-shaped latch elements 23. As the latter are pivoted at 34-34 to the carrier frame and 50 as their friction rollers 35, or like parts are beyond the bars 33, when the bolts are in their outermost positions the latch elements cannot be raised.

If the carrier be at the right hand station as shown in Fig. 1, it is normally despatched therefrom by pulling down upon the propelling cord 36, which drives forward the chaser or follower 37 in a known manner through the instrumentality of cord 38, pulley block 39, etc., and the chaser engages the lever 40 at the right hand end of the carrier, to thereby pull outwardly link 41 of said end and swing up the friction roller 35 of the latch out of engagement 60 with its hook 24. The chaser is thereafter

free, of course, to propel the carrier from the station. When, however, the basket has been lowered it has been found desirable to provide some means to prevent the despatch of the carrier from the station under such conditions, and in the patent to McCormick, Number 896,747, dated August 25, 1908, there is shown a device intended for this purpose. It, however, is adapted to act upon the latch element at but one end of the 70 carrier; this end being of course the one at which the basket is lowered.

It is desirable under certain conditions, as for example where the line-wire does not extend to a balcony or the like, to provide 80 means for lowering the basket or receptacle at both ends of the line. If now such a device as is shown by McCormick be used to prevent inadvertent despatch of the carrier from one station, there will, in the absence 85 of provisions such as are hereinafter described, be nothing to prevent the despatch of a carrier of the McCormick type from the other station, when the basket has been lowered thereat, and the present invention 90 aims to provide a locking means whereby the inadvertent or basketless despatch of the carrier from either station is rendered 95 substantially impossible.

Let us refer again to Figs. 2 and 4. Herein, it will be observed, the right hand bolt 29 has the inner end thereof shaped for engagement with the cam acting surface of the extension 15' of the dog 15, above referred to, so that when the latter is raised, bolt 29 is driven outwardly, while when it is lowered, a spring 42 thereon, which bears against a collar 43 on said bolt, returns the bolt to its inner or normal position. A depending extension of this collar serves as 105 a stop to limit the inward movement of said bolt, as shown in Fig. 4; while a grooved roller receives the upward thrust of the inner end of the bolt when the cam 15' is acting thereupon. The safety bolt 29 also has 110 secured thereto, as by means of a set-screw, a collar 44 to which is attached a bent rod 45 which extends out through a suitable opening in the carrier casing and thence runs parallel therewith toward the bolt 30. 115 The latter is substantially similar to bolt 29, save that it is shorter, and has pivotally and slidably connected thereto at 45 a forked lever 46, which is pivoted at 47 to the carrier frame or casing and extends out there-through; being connected to the end of the rod 45 at 48. By reason of this connection between the bolts 29 and 30, when bolt 29 is driven outwardly as aforesaid, bolt 30 is also moved into locking engagement with 120 the left hand latch member or element 23, so that when the dog 15 is in its upper position, which is normally only when the basket has been detached from the carrier, both latch members 23 are held against move- 125 130

ment and hence it makes no difference at which station the basket is lowered, its carrier cannot normally be despatched until said basket has been again secured to said carrier.

Having thus described my invention what I claim is:—

1. Carrier despatch apparatus comprising a track, a station at substantially each end of said track, each of said stations having a latch engaging part, a carrier to ride on said track and having a pivoted latch at each end of said carrier adapted for locking engagement with the corresponding latch engaging part at one of said stations, a receptacle, an automatic lock to connect said receptacle and carrier together, said lock having a part, a determined movement of which disconnects said carrier and receptacle, a plurality of interconnected means to lock both of said pivoted latches against determined movements thereof, and connections between said last mentioned means and said part.
2. Carrier despatch apparatus comprising a track, a carrier to ride on said track and having a pivoted latch at each end of said carrier, a receptacle, an automatic lock to connect said receptacle and carrier together, said lock having a part, a determined movement of which disconnects said carrier and receptacle, slidably mounted bolts to lock both of said pivoted latches against determined movement thereof, and connections between said bolts and said part.
3. Wire-line carrier despatch apparatus comprising a track, a station at each end of said track, each of said stations having a latch engaging part, and a carrier having a detach-

able receptacle, an automatic locking device to alternately connect said receptacle to and release said receptacle from said carrier, a movably mounted latch at each end of said carrier, each of said latches being adapted for locking engagement with the corresponding latch engaging part at one of said stations, means to hold both of said latches against movement in a determined direction and connections between said last mentioned means and an integral part of said locking device whereby each of said latches is held against said movement thereof when said receptacle is released from said carrier, said connections being carried by said carrier and being separate from the receptacle thereof.

4. The combination of a carrier for wire-line apparatus comprising a detachable receptacle, an automatic locking device to alternately connect said receptacle to and release said receptacle from the carrier proper and a latch part pivoted to each end of said carrier, with two latch parts, one at each end of the wire-line and adapted to respectively engage said pivoted latch parts, and means, controlled directly by a part of said locking device, for preventing the inadvertent disengagement of whichever set of said latch parts is in operative engagement, when said locking device is in its receptacle releasing position, said means being carried by said carrier and being separate from the receptacle thereof.

In testimony whereof I have affixed my signature, in the presence of two witnesses.

GARY S. POWELL.
